US0D1000194S

(12) **United States Design Patent** (10) **Patent No.:** **US D1,000,194 S**
(45) **Date of Patent:** **** Oct. 3, 2023**

(54) **SHAKER AGITATOR**

(71) Applicant: **Takeya USA Corporation**, Costa Mesa, CA (US)

(72) Inventor: **Chia Hung Hsu**, Irvine, CA (US)

(73) Assignee: **Takeya USA Corporation**, Costa Mesa, CA (US)

(**) Term: **15 Years**

(21) Appl. No.: **29/745,900**

(22) Filed: **Aug. 10, 2020**

(51) LOC (14) Cl. **31-00**

(52) U.S. Cl.

(57) **CLAIM**

The ornamental design for a shaker agitator, as shown and described.

DESCRIPTION

FIG. 1 is a side perspective view of a shaker agitator embodying my new design;

FIG. 2 is a side perspective view thereof from another viewing angle;

FIG. 3 is a left elevation view thereof;

FIG. 4 is a right elevation view thereof;

FIG. 5 is a front elevation view thereof;

FIG. 6 is rear elevation view thereof; and,

FIG. 7 is a bottom plan view thereof.

The broken lines in the drawings illustrate portions of a shaker agitator that form no part of the claimed design.

1 Claim, 4 Drawing Sheets
